UNITED STATES PATENT OFFICE.

WILLIAM WARNER BODEN, OF BERWICK, PENNSYLVANIA.

ADJUSTABLE ELECTRIC-LIGHT FIXTURE.

1,189,044.

Specification of Letters Patent. Patented June 27, 1916.

Application filed August 31, 1914. Serial No. 859,465.

To all whom it may concern:

Be it known that I, WILLIAM W. BODEN, a citizen of the United States, residing at Berwick, in the county of Columbia, State 5 of Pennsylvania, have invented certain new and useful Improvements in Adjustable Electric-Light Fixtures; and I do hereby declare the following to be a full, clear, and exact description of the invention, such as 10 will enable others skilled in the art to which it appertains to make and use the same.

This invention relates to adjustable electric light fixtures and particularly to those of the dome type.

15 The object of the invention resides in the provision of an electric light fixture embodying an improved construction whereby the lighting elements thereof can be adjusted vertically according to the particular conditions under which the fixture may 20 be used.

With the above and other objects in view the invention consists in the details of construction and in the arrangement and combination of parts to be hereinafter more 25 fully described and particularly pointed out in the appended claim.

In describing the invention in detail reference will be had to the accompanying 30 drawings wherein like characters of reference denote corresponding parts in the several views, and in which—

Figure 1 is a view in elevation of an electric light fixture constructed in accordance 35 with the invention; Fig. 2, a vertical section of the fixture.

Referring to the drawings the improved fixture is shown as comprising an interiorly threaded ring 10 provided with screw openings 11 whereby same may be secured to a ceiling, which latter is indicated at 12. Threaded in the ring 10 is the upper end of 40 a tubular member 13, the lower end of said member having threaded therein a ring 14.

45 Slidably mounted in the member 13 is a tubular member 15, having threaded on its upper end a ring 16 which overlaps the flange 14 so that the tubular member 15 cannot be disengaged from the tubular member 13 by downward movement of the former. Encircling the tubular member 15 and bearing 50 at its upper end against the ring 16 and at its lower end against the ring 14 is counterbalancing spring 17. Threaded on the

lower end of the tubular member 15 is a 55 head 18 provided with a plurality of interiorly threaded sockets 19 in which are mounted respectively incandescent lights 20. The head 18 is also provided on its lower end with a gripping knob 21 for convenience 60 in moving the tubular member 15 up and down as will be obvious. Mounted on the head 18 are brackets 18' and secured to these brackets is a shade or dome 22. The joint between the tubular member 13 and ring 10 65 is hidden by means of a fancy cover plate 23 secured in place by a set screw 24 carried thereby and adapted to impinge against the tubular member 13. The conducting wires are indicated at 25 and pass through 70 the tubular members 13 and 15 and are connected to the line wires 26 at one end and to the light 20 at their other end. Mounted in the lower end of the tubular member 13 is a set screw 27 adapted to impinge against 75 the tubular member 15 to secure the latter in a desired adjusted position.

By providing the counterbalancing spring 17 it will be apparent that the upward adjustment of the member 15 will be facilitated.

What is claimed is—

An electric light fixture comprising a tubular member having means at one end for securing same to a ceiling and an inwardly 85 directed flange at its other end, a set screw in said flange, a second tubular member slidably engaged within the first named tubular member and having a circumscribing flange on the end thereof movable within the 90 first named tubular member, said second tubular member being engageable by the set screw to lock said member against movement relatively to the first member, a spring 95 encircling the second tubular member and bearing at one end against the flange of the first named tubular member and at its other end against the flange of the second named tubular member, a head threaded on the other end of the second named tubular member, 100 threaded sockets embodied in said head, and a shade secured to the head.

In testimony whereof I affix my signature, in the presence of two witnesses.

WILLIAM WARNER BODEN.
